UNITED STATES PATENT OFFICE.

GEORGE E. STEUDEL, OF MILWAUKEE, WISCONSIN.

HOT-BLAST STOVE.

Application filed July 21, 1924. Serial No. 727,203.

To all whom it may concern:

Be it known that I, GEORGE E. STEUDEL, a citizen of the United States, residing at Milwaukee, in the county of Milwaukee and

5 State of Wisconsin, have invented certain new and useful Improvements in Hot-Blast Stoves, of which the following is a specification.

My invention relates to blast stoves and 10 has particular reference to an improvement in the brick checker work used in the regenerative chambers of hot blast stoves.

The principal object of my invention is 15 the provision of checker work placed in the stove in such manner that the vertical flues or channels extending through the checker work have communicating passages with each other so that the heated gases and products of combustion passing through the 20 chamber in one direction can spread out over the entire cross-sectional area and the air blast passing in the opposite direction also can pass from one flue to another, and spread out over the entire cross sectional 25 area of the regenerative chamber.

Heretofore it has been common practice 30 in arranging the bricks forming the checker work to place them in courses in edge to edge and end to side relation with each other, this arrangement extending from the bottom to the top of the regenerative chamber thereby forming passages or flues which are 35 substantially square in cross section, the said flues or passages being continuous from the top to the bottom of the regenerative chamber. In this form of construction the gas or air flowing through the long flue will 40 flow faster in the center than along the sides, especially where the bricks making up the sides of the channel are rough, so that the gas which passes through the channels gives up its heat to the bricks with which it comes in contact and in turn the slow moving gas adjacent the bricks acts as an 45 insulator and prevents the gas in the center of the flue from giving off its heat to the bricks. In other words, the gas channels as it passes through the checker work. In my improved method of forming the flues 50 through the regenerative chambers I provide courses having bricks of one-half the usual height placed in a plurality of courses and in regular positions in each horizontal course, the total number being eight courses 55 so as to cover the entire cross-sectional area of the horizontal chamber so that communica-

cating passages are formed in the checker work at regular belts which will allow the gas to pass from one flue to another or spread throughout the entire cross-sectional area of the regenerative chamber as 60 the gas passes through one of these belts. The courses of brick are so positioned that there is no material lessening of the strength of the checker work construction so that 65 there is no danger of the checker work collapsing and filling up the flues and in this manner I am able to cause a flow of gas to be distorted as it flows through the regenerative chamber and thereby allowing the 70 brick work to absorb the heat from the burned gases and products of combustion more quickly than it otherwise would do, and also allowing the air, when the hot blast stove is on blast, to absorb heat more quickly 75 from the checker work, thereby resulting in a stove of higher efficiency than what has been common heretofore.

Another and further object of my invention is the provision of a plurality of courses 80 of brick making up the checker work of half bricks, so that there is a regular belt throughout the checker work in the regenerative chamber through which the gases and air can spread from one flue to another 85 as the gases pass through the regenerative chamber, and thus effectually prevent the channeling of the gas through the center of the flues.

These and other objects of my invention 90 will be more fully and better understood by reference to the accompanying drawings, and in which—

Figure 1 is a vertical sectional view 95 through a hot blast stove;

Figure 2 is a transverse sectional view of the first course of brick making up one of the belts of my improved construction;

Figure 3 is a transverse sectional view on lines 3—3 of Figure 2;

Figure 4 is a transverse sectional view of the second course used in my improved construction;

Figure 5 is a vertical sectional view on lines 5—5 of Figure 4;

Figure 6 is a partial transverse sectional view of course No. 3 of my improved construction.

Figure 7 is a partial transverse sectional view of the fourth course of my improved construction.

Figure 8 is a partial transverse view of

the fifth course of bricks making up the checker work;

Figure 9 is a sectional view showing the sixth course of bricks;

6 Figure 10 is a sectional view of the seventh course;

Figure 11 is a view of the eighth course of bricks making up the checker work; and

10 Figure 12 is a vertical sectional view showing a belt of the courses heretofore illustrated extending across the entire regenerative chamber.

Referring now specifically to the drawing, a hot blast stove shell 10 is shown, having openings 11 and 12 therein through which gas and air flow into and out of the hot blast stove, and having the usual brick lining 13 with a vertical wall 14 placed therein adjacent a passage 15, with the usual brick or checker work in the regenerative chamber of the stove. In the preferred form I show two belts 16 and 17 in the regenerative chamber, having bricks of half the usual height placed in spaced relation with each other and in a plurality of horizontal courses throughout the belt, preferably eight in number, although any number can be used, so that in each belt the air or gas can spread out into substantially all of the flues and throughout the entire cross sectional area of the regenerative chamber.

Referring now to Figures 2 and 3 and in which the first course of one of the belts is illustrated, it will be noted that this course comprises a plurality of rows of brick 18, 18 in spaced parallel relation with each other, and extending in a direction toward the passage 15 of the stove 10, and a plurality of rows of brick 19, 19 in spaced relation with each other extending transversely across the stove 10 at right angles to the rows 18, 18, the bricks making up these rows being of the usual size and placed in registered edge to edge vertical relation with each other, the bricks making up each of these rows being placed in end to side horizontal relation with each other, so that the flues 20, 20 are formed which are substantially square in cross sectional shape, and which extend vertically through the regenerative chamber of the stove 10. Each alternate row 18 has a plurality of bricks 21, 21 laid therein one-half the height of the other bricks used in making up this course, these half bricks being placed in alternate relation with full size bricks in the row 18, so that when the checker work is completed, each flue 20 adjacent the half bricks has a communicating passage or port formed in the checker work, so that gas and air can pass from one flue to another over the tops of the half bricks. It will be understood that in laying these courses the vertical joints between the bricks are broken, that is, the courses are so placed that the vertical

joints between the bricks are out of alignment with each other so that the whole checker work is more securely held together against side slipping. Filler blocks of proportionate size are placed around the 70 marginal edge of each course to insure the proper filling of the regenerative chamber, all of which is common practice in the building of this checker work.

The second course of bricks (see Figures 75 4 and 5) is laid similarly to the first course and comprises a plurality of rows 22, 22, extending parallel to the row 18 of the first course and in registered relation therewith, and a plurality of other rows 23, 23 which 80 extend parallel to and in vertical registered relation with the rows 19, 19 in the first course, with half bricks 24, 24 placed in the rows 22 in spaced alternate relation with the full height bricks, the rows 22, 22 in 86 which the half bricks are used in this course being in vertical offset relation with the rows 18, 18 in the first course in which the half bricks are used.

Referring now to Figure 6 in which the third course of bricks is illustrated, a plurality of rows of bricks 25, 25 are shown with rows 26, 26 extending in the opposite direction and having half bricks 27, 27 placed therein, these half bricks being in the same 90 relative position as the half bricks in the courses heretofore described with relation to each other and are placed in the rows which are in vertical alignment with the rows of brick in which the half bricks 21 are placed 100 in the first course but are in offset spaced relation with these bricks being above the full bricks set in the rows 18, 18 in the first course.

Referring now to Figure 7 in which the fourth course is illustrated, a plurality of rows of bricks 28, 28 are shown which extend parallel to the rows 25, 25 in the first course with other rows 29 extending at right angles thereto, and having half bricks 30, 30 positioned therein, the rows 29 in this course being in vertical alignment with the rows 22 in the second course, and the half bricks being above the full size bricks used in this course and in offset relation with the 110 half sized bricks in the rows 22, 22 in the said second course.

Referring now to Figure 8 in which the fifth course is illustrated, a plurality of rows 31, 31 are used which extend toward the passage 15 and a plurality of other courses 32, 32 which extend at right angles thereto and within which half bricks 33, 33 are positioned, these half bricks being in spaced alternate relation with each other, the same as in the other courses with the exception that the half bricks are used in the transversely extending rows 32, 32.

Referring to Figure 9 in which the sixth course is illustrated, a plurality of trans-

versely extending rows 34, 34 are used and a plurality of other rows 35, 35, extending at right angles thereto each of said rows being in vertical alignment with the lower 5 rows with half bricks 36, 36 positioned in spaced relation with each other in each alternate row 34, 34, these half bricks being positioned in vertical alignment with the rows 32, 32, in the fifth course and in offset relation with the rows in which the half bricks 10 are used in the fifth course.

In Figure 10 is illustrated the seventh course in which transversely extending rows of brick 37, 37 are shown with other 15 rows 38, 38 extending at right angles thereto, and half bricks 39 being placed in spaced relation in the course in vertical alignment with the rows 32 in which the half bricks in the fifth course and directly above the 20 full size bricks used in the rows 32 in the fifth course.

Referring now to Figure 11 in which the eighth course is illustrated, a plurality of rows 40—40 of brick is shown, having transversely extending rows 41 with half bricks 42 positioned in spaced relation with each other in this course, these half bricks being in the same vertical alignment as the rows 34 in which the half bricks making up the 25 sixth course are used, but being in offset relation with said half bricks and immediately above the full height bricks used in this course.

The checker work above the eighth course 30 is built up in precisely the same manner with full sized bricks in end to side relation with each other until the first course of the belt 17 is reached whereupon the same order of arrangement is followed as that heretofore described for the belt 16. Above this belt 17 the checker work is continued in the usual manner to the top of the regenerative chamber. The number and arrangement of the courses may be varied from what is 35 shown and described, and it may be found desirable in smaller stoves to use only three or four courses to each belt, and more than two belts may be used in each regenerative chamber if desired.

50 It will thus be understood that I provide communicating ports through the checker chamber in which all of the vertical flues are connected, except a few flues around the outer periphery of the checker work and through which very little air and gas flow 55 during the operation of the hot blast stove.

In the operation of the stove, the gas or air enters at the bottom of the stove and flows upward or downward through the 60 checker work, depending upon whether gas or air is flowing through the stove and through the checker work until it reaches one or the other of the belts 16 or 17, whereupon the gas spreads out over the tops of 65 the half bricks and any tendency to chan-

nel the gas is broken up so that I am able to secure a much more efficient and effective operation of the hot blast stove than what has been possible heretofore.

While I have described more or less precisely the details of construction, I do not wish to be understood as limiting myself thereto, as I contemplate changes in form and the proportion of parts and the substitution of equivalents as circumstances may 70 suggest or render expedient without departing from the spirit or scope of my invention.

I claim:

1. Checker work for hot blast stoves, comprising in combination horizontal courses of brick extending at right angles to each other and in vertical alignment with each other, whereby flues are formed through said checker work, the said checker work having 80 bricks of unequal height placed therein, whereby communicating passages are formed between the said flues in said checker work.

2. Checker work for hot blast stoves, comprising in combination courses of brick placed in horizontal courses and extending at right angles to each other and having bricks of one-half the height of the bricks making up the courses placed in predetermined position in said courses, whereby communicating passages are formed with the vertical flues and extending through the said checker work.

3. Checker work for hot blast stoves, comprising in combination of bricks laid in horizontal courses in said hot blast stove, each course comprising parallel rows placed at right angles to each other whereby flues are to be formed in said stove and a plurality of belts of checker work, having bricks of unequal height in said belt, whereby gas may pass from one flue to another in said belt.

4. Checker work for regenerative chambers of hot blast stoves, comprising in combination a plurality of horizontal courses of brick, in vertical registered relation with each other each course comprising a plurality of rows of brick and extending at 110 right angles to each other, and half bricks placed in one of said rows, whereby gas may pass from one flue to another in said checker work.

5. Checker work for regenerative chambers comprising horizontal courses, each course having a plurality of rows of brick in spaced parallel relation with each other extending in one direction and a plurality of rows of brick in spaced parallel relation with each other and at right angles to the said first mentioned rows, whereby flues are formed in said checker work, a part of said bricks in the said rows being of one-half height of the bricks used in the other courses 120 125 130

whereby communicating ports are formed in the walls of the said flues.

6. Checker work for regenerative chambers comprising horizontal courses, each course having a plurality of rows of brick in spaced parallel relation with each other extending in one direction and a plurality of rows of brick in spaced parallel relation with each other and at right angles to the said first mentioned rows, whereby flues

are formed in said checker work, a part of said bricks in the said rows being of one-half height of the bricks used in the other courses whereby communicating ports are formed in the walls of the said flues, the bricks in said courses being placed in end to side relation with each other.

Signed at Milwaukee, Wisconsin, this 11th day of July, 1924.

GEORGE E. STEUDEL.
